UNITED STATES PATENT OFFICE.

CHARLES J. JAGER, OF BOSTON, MASSACHUSETTS.

VAPORIZING-CARBURETER FOR INTERNAL-COMBUSTION ENGINES.

SPECIFICATION forming part of Letters Patent No. 774,079, dated November 1, 1904.

Application filed November 7, 1903. Serial No. 180,166. (No model.)

To all whom it may concern:

Be it known that I, CHARLES J. JAGER, a citizen of the United States, residing at Boston, in the county of Suffolk, State of Massachusetts, have invented a certain new and useful Improvement in Vaporizing-Carbureters for Internal-Combustion Engines and the Like, of which the following is a specification, reference being had therein to the accompanying drawings.

The invention in general consists in a vaporizing-carbureter which has been designed for employment more especially in connection with internal-combustion engines, although it is not necessarily restricted to this precise use.

More particularly, the invention consists in a carbureter having a valve arrangement of the novel and improved construction which I presently shall describe and which maintains uniformity in the relative proportions of air and vapor in the gaseous mixture constituting the fuel that is supplied to the engine or other place of consumption throughout variations in the speed of the engine or otherwise in the rate of consumption and accompanying variations in the rate of flow of air through the carbureter.

I have shown in the drawings a carbureter embodying the invention in the form in which I have actually reduced the invention to practice. While I shall carefully explain the construction of the said embodiment as the same is illustrated in the drawings, it is to be understood that the precise form, construction, and arrangement which are illustrated in the drawings are not of the gist of the invention and that various details which are shown and to which I shall make reference may be changed or omitted without involving departure from the spirit of the invention.

In the drawings, Figure 1 shows in vertical section a carbureter containing the embodiment aforesaid of the invention. Fig. 2 shows detached the movable valve.

Having reference to the drawings, at *a* is represented a portion of a fuel-supply pipe which in practice is connected with the cylinder or other combustion-chamber of an engine of the class aforesaid. The passage through

the said pipe constitutes the main fuel-supply passage. Within the pipe *a* rises centrally a pipe *b*, which latter in practice is supplied with the hydrocarbon from which is produced the vapor that unites with the air flowing 55 through the pipe *a* to form the gaseous mixture constituting the fuel which is consumed in the engine. The pipe *a* is formed with an opening *a'* at one side thereof and with a projecting rim *a''* around the said opening. To 60 the outer portion of the said rim is applied the flange *c*, that is formed at one end of a stand *c'*, the said stand having also a circular enlargement or boss *c''*, which fits within the opening *a'*. The stand *c'* has a longitudinal 65 bore or passage-way *c'* formed therethrough, such passage-way opening at the inner end of the boss or enlargement *c''*. The lower end of the pipe *b* is bent so as to extend at right angles with respect to the main portion 70 of such pipe and extends into the opening *a'*, its extremity being inserted into the inner end of the passage-way *c'* and being secured fixedly therein. The outer end of the passage-way *c'* is enlarged to form a valve-chamber *c''*, and 75 within the said valve-chamber works the needle-valve *c''*. The inner end of the stem of the needle-valve serves to control the flow of hydrocarbon into and through the passage-way. An entrance-port *c''* communicates with 80 the valve-chamber at the outer side of the valve-seat. The said entrance-port extends downward through the top of the stand *c'* to the valve-chamber. The stand *c'* supports a glass cylinder *d*, the latter constituting the 85 body of a cup which in practice contains a quantity of the hydrocarbon with which the pipe *b* is supplied. The stand *c'* is formed at its upper side with a seat for the lower end of the glass cylinder *d*, a ring of cork *d'* being 90 applied to the said seat to constitute a cushion and packing for the lower end of the glass cylinder. A cap *d''* is applied to the upper end of the glass cylinder, a similar ring of cork *d''* being interposed between the said upper end and the said cap. The space within the cylinder *d* is known usually as the "float-chamber," it containing, in practice, a float, and having in connection therewith a valve 95 by means of which communication with a 100

storage-receptacle is controlled, the action being to maintain automatically a constant level of the hydrocarbon within the cylinder in order that the hydrocarbon may always rise 5 within the vertical portion of the pipe *b* to within a predetermined distance of the upper end of the said pipe. The float, &c., are well known and form no part of the invention. Accordingly I have omitted them from the 10 drawings as unnecessary to be shown herein.

In operation the hydrocarbon flows from the float-chamber through the port *c*⁶ at the bottom thereof into the valve-chamber *c*⁴ and past the valve through the passage-way *c*³ into 15 the pipe *b*. The air which travels through the pipe *a* under atmospheric pressure on its way to the engine takes the hydrocarbon by aspiration from the upper end of the pipe *b* in the form of vapor. For the purpose of 20 controlling the richness of the mixture the needle-valve *c*⁵ is provided, in connection with the passage-way *c*³, in order that by adjustment thereof the rate of flow of the hydrocarbon from the float-chamber through the 25 passage-way *c*³ into the pipe *b* may be regulated at will. The knurled head of the stem of the said valve is located at the outer end of the stand *c*¹ and is accessible exteriorly of the carbureter for convenience of manipulation 30 and in order to enable the rate of flow to be changed whenever deemed necessary in the use of the carbureter.

Within the pipe *a* between the hydrocarbon-pipe *b* and the inlet end of the said pipe *a*—that is to say, below the said pipe *b* in the drawings—a reticulated or foraminated diaphragm *e* is located. Preferably this diaphragm is formed of fine wire-gauze. This diaphragm serves a twofold purpose. It 35 strains solid matters from the air flowing through the pipe *a* and in addition breaks up the body or volume of air, dividing it into a number of small streams or currents and causing a lively movement of the air within the 40 subsequent portion of the pipe as it passes the upper end of the hydrocarbon-pipe *b*. Thereby a more perfect intermingling of the air with vapor from the hydrocarbon within pipe *b* is insured. For the purpose of permitting 45 additional volumes of air to enter the pipe *a* when required a series of inlet-ports *a*³ *a*³ is formed through the shell of the pipe *a* around the vertical portion of the hydrocarbon-pipe *b*. In connection with the said inlet-ports *a*³ I employ for the purpose of regulating 50 automatically the inflow of air through the said ports the valve which I will now describe. The said valve consists, essentially, of a cylinder *f*, having a sliding fit within the 55 interior of the pipe *a* and having its upper end furnished with a reticulated or foraminated diaphragm *f*⁷, preferably of finely-meshed wire-gauze. The valve occupies normally a lowered position in which its lower end rests 60 upon a ledge *a*⁴, that is formed upon the in-

terior of the pipe *a*. In this position the shell of the valve closes the air-inlet ports *a*³. The valve occupies this position during the running of the engine at slow speed. When the speed of the engine increases, the air 70 passes through the pipe *a* on the way to the engine with a correspondingly-increased rate of flow. With this increased rate of flow it tends to take up a greater proportion of hydrocarbon vapor, which would render the fuel 75 too rich for satisfactory results in its combustion within the engine if not compensated for. The increased velocity of the flow of the air through the pipe *a* operates, however, to lift the valve *f* to a degree corresponding with 80 the increase in the rate of flow of the air through the pipe *a*, thereby uncovering the air-inlet ports *a*³. The uncovering of the said air-inlet ports *a*³ permits air to enter there-through. In this manner the relative proportions of air and vapor in the fuel are 85 kept the same, whatever may be the rate of flow to the engine. The diaphragm *f*⁷ of wire-gauze is important, inasmuch as the air not only acts upon the same with a tendency 90 to lift the valve, but in passing through the meshes thereof the air and vapor are caused to become thoroughly intermixed and commingled, so that the fuel is of uniform composition throughout its volume. 95

For the purpose of limiting the upward movement of the valve *f* within the pipe *a* a stop is provided. In the present instance the said stop is constituted by a split ring *h* of spring-wire, which is seated within a groove 100 *h*⁷, that is formed for its reception in the inner wall of the pipe *a*. A portion of the thickness of the wire of the said ring projects inwardly into the passage of the pipe *a*, so that when the valve rises within the said pipe the 105 upper end of the valve shall encounter the said portion of the ring.

The diaphragm *e* has another function in addition to those which have previously been referred to herein. In practice in case of 110 overflow of hydrocarbon at the upper end of the pipe *b*, which may occur either accidentally or intentionally, the portion of hydrocarbon which escapes from the upper end of the pipe *b* will drip onto the diaphragm *e* and 115 be caught thereby. This portion of hydrocarbon being exposed advantageously to the volume of air passing through the fuel-supply pipe will be taken up thereby in the form of vapor. Thereby accumulation of liquid 120 hydrocarbon in a bend or the like of the fuel-supply pipe will be prevented. Moreover, when the overflow is caused to take place prior to starting up the engine, the combination of the vapor from such overflow with the 125 air passing through the fuel-supply pipe *d* will produce a rich fuel-mixture, facilitating thereby initial movements of the engine. The overflow may be caused to occur intentionally in practice, as in starting up by de- 130

pressing by hand the cork or float (not shown) within the float-chamber, as by means of the pin d^9 , working through a hole at the center of the cap d^2 and normally supported in an uplifted position by means of the expansion spiral spring d^8 . The said spring encircles the upper portion of the length of the pin, being partly received within the enlarged upper portion of the bore through the central projection or knob b^{21} of the cap d^2 and being located between the head of the pin and the bottom of the enlargement of the said bore.

With each arrest in the inflow of the gaseous fuel into the engine on the closing of the inlet-port of the engine the gaseous contents of the fuel-supply pipe a experience a check in their flow through such pipe. This check is accompanied by a species of recoil which tends to produce outward flow of the said contents through the air-inlet ports a^3 when the latter are open. Thus the air-inlet ports a^3 being open at each arrest of the inflow of the fuel into the engine a certain portion of the contents of the pipe a passes out through the said air-inlet ports a^3 . For the purpose of confining the fuel mixture which thus passes out through the air-inlet ports a^3 , so as to prevent the escape of the same into the atmosphere and of causing the same to return subsequently into the pipe a , a casing-tube g is placed around the pipe a , the lower end of the casing-tube resting upon an exterior ledge a^5 , with which the pipe a is provided below the level of the air-inlet ports a^3 . A ring or cap g' closes the opening between the pipe and casing-tube at the top of the latter. To permit of the entrance of air into the space between the pipe and the casing-tube, air-inlet openings g^2 are formed through the casing-tube near its upper end. Air entering through the said openings g^2 and filling the space between the pipe a and the casing-tube g flows when permitted so to do by the uplifting of the valve f from the lower portion of the said space through the air-inlet ports a^3 to the interior of the pipe a . It will now be clear that when the check in the onflow of the gaseous contents of the pipe a takes place and the recoil causes a portion of the said contents to issue through the air-inlet ports a^3 into the space that is inclosed by the casing-tube g

such portion is retained within the said space. The next onward movement of the contents of the pipe a will draw the portion of gaseous mixture which thus escapes through the ports a^3 back within the pipe a together with an additional quantity of air.

I claim as my invention—

1. A vaporizing-carbureter having the main passage, the hydrocarbon-pipe located within the said passage, the air-inlet ports to admit additional quantities of air, and the automatic valve provided with the reticulated diaphragm through which the combined air and vapor flow.

2. A vaporizing-carbureter having the main passage, the hydrocarbon-pipe located within the said passage, the air-inlet ports to admit additional quantities of air, the automatic valve provided with the reticulated diaphragm through which the combined air and vapor flow, and a valve to regulate the rate of flow through the said hydrocarbon-pipe exteriorly accessible for purposes of adjustment.

3. A vaporizing-carbureter having the main passage, the hydrocarbon-pipe located within the said passage, the reticulated diaphragm adjacent the said pipe and through which the air passes before reaching the discharging end of the said pipe, the air-inlet ports to admit additional quantities of air, and the automatic valve provided with the reticulated diaphragm through which the combined air and vapor flow.

4. A vaporizing-carbureter having the main passage, the hydrocarbon-pipe located within the said passage, the reticulated diaphragm adjacent the said pipe and through which the air passes before reaching the discharging end of the said pipe, the air-inlet ports to admit additional quantities of air, the automatic valve provided with the reticulated diaphragm through which the combined air and vapor flow, and a valve to regulate the rate of flow through the said hydrocarbon-pipe exteriorly accessible for purposes of adjustment.

In testimony whereof I affix my signature in presence of two witnesses.

CHARLES J. JAGER.
